ACCUMULATOR WITH DIAPHRAGM STABILIZER

Granville S. Knox, Glendale, Calif., assignor to Hydrol Company, Los Angeles, Calif., a corporation of Ohio

Application August 16, 1954, Serial No. 450,139

14 Claims. (Cl. 138—30)

This invention has to do generally with accumulators or pulsation dampeners and is more particularly concerned with such devices wherein diaphragm stabilizing means are included, as well as to the stabilizing means, per se.

The invention is particularly well adapted to handle the severe service requirements of and to withstand the severe conditions encountered in pumping mud laden fluid during well drilling operations, and therefore I have illustrated and will describe an embodiment especially suited to that use, though this is not to be construed as limitative.

In the above environment, dampeners are installed in output lines of reciprocating-plunger, mud or slush pumps, to smooth out pressure peaks. The pre-charged surge chamber effectively eliminates surging and water hammer in the rotary hose and mud lines, resulting in longer service life and less maintenance trouble and expense as regards the pumps, the rotary hose, the swivel packing, etc. all as is well understood in the art.

In my copending application on Accumulator or Pulsation Dampener, Serial No. 327,280, filed December 22, 1952, now Patent No. 2,757,689, August 7, 1956, I have shown, described and claimed a device having, among other features and advantages, superior characteristics as regards capacity and efficiency, as well as avoidance of harmful folding and wrinkling of the diaphragm, in spite of its advantageous length of stroke.

In that application it is pointed out that undue accumulation of sediment in the body chamber is prevented by the sweeping effect of the diaphragm when the diaphragm is forced downwardly by gas pressure after the pumps have shut down. It is also set forth that certain parts of the device are so shaped and relatively located that sediment entering the chamber is evenly distributed to the extent that there are no harmful local accumulations of sediment during operation. Thus the accumulator was said to be, in all essence, "self-cleaning."

This all proved to be true in actual practise except when certain types of mud laden fluid were encountered. For instance, peculiar results followed when the mud-laden fluid tended to gel when it was unagitated. Such was the case when bentonite was one of the constituents of the drilling mud, and I will therefore discuss the problem in that light, without inferring that a stable suspension, such as this, is the only cause of the difficulty or that my remedy applies only when the suspension is stable.

Bentonite is a soft, porous, moisture-absorbing rock, composed essentially of clayey materials, having the property of thixotropy, that is, of becoming fluid when agitated—the change being reversible. Thus, when a body of bentonite-laden fluid gathered in the accumulator chamber below the diaphragm, it had zones of differential viscosity; that is, the material in the relatively quiet zone around the periphery of the chamber became gel-like, whereas the material in the central zone or core became fluid due to the agitation caused by the more pronounced movement of the central portion of the diaphragm and to the jetting effect as the material was discharged from the mud chamber.

As a result, when the pressure of the gas above the diaphragm became effectively predominant upon temporarily shutting down the pumps, the central portion of the diaphragm was plunged down through the low viscosity zone, pulling the upper part of the bladder away from the upper wall of the housing. The elongation of the diaphragm necessary to seat the stopper was thus accomplished by displacement of the upper extent of the bladder rather than by a stretching of the lower extent thereof, as was intended and was normally the case. This left an annular body of gel-like material about the elongated diaphragm. The bladder, being unstretched, had no "snap-back" characteristics when pressure conditions on opposite sides of the diaphragm were subsequently equalized, and therefore failed to return to a position of equilibrium. As a consequence, its upper extent remained in spaced relation with respect to the upper wall of the housing and an annulus of gel-like material remained around the lower extent. During subsequent cycles of operation additional quantities of the gel-like material gathered between the upper extents of the housing and bladder, further exaggerated the undesirable effect. And, of course, each time the volumetric capacity of the diaphragm bladder was reduced by an ever enlarging annulus of sediment, the contained pressure was increased until it so nearly approached the peak pressure of the pumped fluid that it offered no effective dampening action.

It is therefore a general object of the present invention to provide means whereby the dampener will continue to function with full efficiency in spite of the fact that the fluid being handled is thixotropic, or of any nature which tends to cause it to accumulate in unduly large amount about the bladder. In other words it cares for conditions where the suspension is stable but its viscosity depends on its degree of agitation, or where the suspension is so unstable that the solids settle out with undue rapidity and "crust" when the fluid is relatively quiescent.

In general, I accomplish the desired result by attaching the center of a stabilizer, preferably in the form of a relatively stiff rubber disk, to the center of the diaphragm at the gas-chamber side thereof and thus in axial alignment with the stopper at the opposite side of the diaphragm. However, the radially outwardly extending portion of the disk is unattached to the diaphragm, thus being movable with relation to the underlying portion of the diaphragm and permitting said underlying portion to retain its full stretch and snap-back capacities. In other words, the stabilizer has the effect of vertically stiffening the central portion of the diaphragm without affecting the elastic characteristics of the lower extent of the bladder wall. At the same time, the stabilizer is preferably capable of limited, resilient deformation to the extent that it may substantially conform itself to the shape of the engaged portion of the bladder and perform its necessary stiffening function without tending to overstress or puncture the bladder. The stabilizer thus creates an enlarged central area which is axially relatively stiff without impairing other desirable characteristics.

If the diaphragm is working in the lower half of the housing during a given period, the stabilizer acts to increase the effective area of the diaphragm insofar as agitation is concerned, thus giving an increased-area zone of relative fluidity and reducing the extent of the quiescent zone. There is, accordingly, less material available for the formation of gel, thus reducing the hazards otherwise resulting from such formation. On the other hand, such gel as may form beneath the diaphragm (and this also applies where the diaphragm may be working in the upper half of the housing where, under certain circumstances, the stabilizer adds nothing to the agitating effect) is, in large part, pushed out of the chamber by the larger-diameter, stiffened portion of the diaphragm, thus reducing

the thickness of the gel-annulus below the danger point, the upper wall of the bladder continuing to hug to the complementary wall of the housing and the lower wall of the bladder being forced to stretch as the stopper approaches and reaches its seat.

The stabilizer is also helpful even though the liquid being handled is entirely free of sediment. For instance, it "irons out" the wrinkles and folds of the diaphragm as they start to form when the diaphragm passes through a median zone, all as will be explained.

I will describe the invention as applied to a pulsation dampener corresponding to the showing of said copending application, with which it is peculiarly well adapted to function, but this is not to be considered as limitative on the broader aspects of the invention.

Other objects and features of novelty will become apparent from the following detailed description, reference being had to the accompanying drawings, in which:

Fig. 1 is a side elevation of the dampener;

Fig. 2 is a top plan view of Fig. 1 partly in broken-away section;

Fig. 3 is an enlarged section on line 3—3 of Fig. 2;

Figs. 4 and 5 are fragmentary views showing the behavior of the diaphragm under certain operating conditions.

The body shell or housing 10 is made up of main section 11, cap section 12, and bottom section 13, the portions of the housing above and below the central axial plane A being considered, respectively, as upper and lower shell-walls 14 and 15. The upper end of section 11 has a relatively large-diameter central mouth 16 which receives the cylindrical plug portion 17 of section 12, while the flange portion 18 of section 12 is bolted to section 11 at 19. The peripheral face 20 of plug portion 17 is annularly spaced from the defining wall 21 of mouth 16 to provide a downwardly opening, annular groove 22 which, as well as counterbore 23, serve to receive and anchor portions of the diaphragm or bladder, as will appear later.

The lower end of section 11 has a relatively small-diameter central mouth 24 adapted to receive the cylindrical plug portion 25 of bottom section 13, the flange portion 26 of section 13 being bolted to section 11 at 27. The joint between sections 11 and 13 is packed off by compressed sealing ring 28. Flange 26 has threaded holes 29 to receive bolts 30 (Fig. 1) whereby the flange 31 of fitting 32 may be fastened to the dampener, this fitting being connected by pipe 32' to the output line (not shown) of a pump or the like. The pipe communicates with the central flow passage 33 extending through bottom section 13.

Walls 14, 15 define a chamber C which has the general shape characteristics of an oblate spheroid with its polar or shorter axis B extending vertically, it being understood that the words "vertical" and "horizontal" are used merely for the purpose of orientation of parts and not in their limited sense. Axial plane A may thus be considered as the equatorial axial plane of chamber C, since the line representing that plane also represents the longer axis of the generating ellipse.

The lower portion of the defining wall of chamber C is preferably slightly modified so that the curved defining wall 34 merges smoothly into a conical surface or zone 34' immediately surrounding the orifice 35 of passage 33, the conical surface smoothly and with stream lines merging into the defining wall of the passage, which latter is in the nature of a venturi, with the venturi streamline restriction 36 at a point near said orifice.

The diaphragm 37 is in the nature of a bladder made of natural or synthetic rubber and is pre-formed, as by molding, so, when it is in equilibrium, it has the shape shown in solid lines (position D) in Fig. 3. The neck 39 and neck flange 40 of the bladder are tightly clamped in groove 22 and counterbore 23, respectively, thus not only positively fixing the upper end of the bladder to

housing 10, but also packing off the joint between sections 11 and 12.

When in position D (that is, when the diaphragm is in equilibrium and thus in the shape it inherently assumes when detached from the housing) its upper portion 41 has an arcuate extent 42 which is complementary to and engages upper shell wall 14. Arcuate portion 42 terminates at 45, lying approximately in plane A, and is connected to base portion 43 by a bend 44, annular as viewed in plan, whose lower edge 45' lies in plane G, and thus below plane A. Each portion of bend 44 is arcuate in vertical cross section, with the centers of cross-sectional curvature lying approximately in plane A. Thus, when the diaphragm is in equilibrium, base portion 43 lies, in major extent at least, within the space bounded by upper portion 42.

Starting from bend 44, the base portion has a conical extent 46 which merges, by way of curved extent 47, into an uppermost, substantially horizontal, but preferably slightly crowned, central extent 48. Embedded in this central extent is a downwardly pointing, conical valve stopper 49 which is rigid in nature and is keyed to the rubber diaphragm at 50. As will later appear, the stopper provides anchoring means for the stabilizer, to be described.

The axes of stopper 49 and passage 33 are coincident with polar axis B. The rubber making up the diaphragm is continued integrally across the lower conical surface 51 of stopper 49 to provide a rubber facing 52 to seat on conical face 34' around orifice 35 when the bladder is in fully distended condition, as represented by the dot-dash position F, thus to close off passage 33 and prevent extrusion of the bladder into said passage.

Opening through cap section 12 and into the bladder, 35 is a fluid flow passage 53, into which a valved fitting 54 is set. Gas such as compressed air or compressed nitrogen is introduced through fitting 54 to provide the pulsation absorbing or dampening medium when surges occur in the fluid admitted through passage 33 to chamber C 40 below the bladder. A gage 55 is in communication through passage 56 with the bladder interior, whereby the gas pressure within the bladder may be ascertained. Preferably, a guard 57 is bolted to cap section 12 to protect fitting 54 and gage 55, the guard having a gage-sighting 45 opening 58.

Stopper 49 is centrally bored and threaded at 65 to take bolt 66. This bolt, in conjunction with flanged, cup-shaped retainer 68, holds the stabilizer, generally indicated at 69, to diaphragm 37. The bottom 70 (Fig. 4) 50 of the cup-portion 71 of retainer 68 engages the upper end 72 of stopper 49, while flange 73 is vertically spaced above and substantially parallel to central crown 48 of diaphragm 37.

Stabilizer 69 is pre-formed as a flat disk of rubber, natural or synthetic, having greater axial stiffness than does the rubber of the diaphragm, and, preferably is somewhat thicker than is the wall of the diaphragm. For instance, it has been found satisfactory, where the diaphragm has a hardness of from 50 to 55 on the durometer 60 A scale, to provide a stabilizer having a hardness of from 72 to 85 on that same scale, though these particular ranges are not to be considered as limitative. Also as 65 illustrative of satisfactory relationships, the thickness of the stabilizer may be in the order of $\frac{1}{2}$ " where the thickness of the diaphragm is in the order of $\frac{5}{16}$ ".

Stabilizer 69 is centrally apertured at 74 to receive cup 71, whereby the stabilizer is held centered with the retainer and hence with the diaphragm, and its inner, annular portion 75 is held down to crown 48 by flange 73, said portion 75 being slightly flexed to conform to said crown. The outer, annular portion 76 extends substantially horizontally when the diaphragm is in equilibrium, there thus being developed an angle of about 30° between said portion and the conical extent 46, though this angle is not critical and, in fact, may be absent where it is desired

that the stabilizer-portion 76 engage wall 46 even when the diaphragm is in equilibrium.

However, it is important that portion 76 be unattached to diaphragm wall 46; that is, portion 76 and wall 46 are to be capable of such relative movement that the stabilizer in no way diminishes the stretchability of wall 46. On the other hand, not only do the inner annular portion 75 of the stabilizer and the retainer flange 73 increase the axial rigidity of central portion 48 of the diaphragm, but also the outer annular portion 76 of the stabilizer axially stiffens or reinforces wall 46 when the diaphragm is moved in a manner to engage that wall.

While the illustrated relative diameters of the diaphragm, at equatorial plane A, and of the stabilizer 69 are not to be considered as limitative, I have found that, for instance, a ratio of about 11 to 9, is especially well adapted to the purpose, this giving a desirable extent of radial extension or overhang of the stabilizer with respect to wall 46. The illustrated ratio (about 5.5 to 9) of the inside diameter of bladder-neck 39 and stabilizer 76, is not at all limitative. However, with this ratio existing it is possible to assemble the relatively large-diameter stabilizer with the diaphragm by bending the stabilizer nearly double and inserting the doubled-up member endwise through the neck. As soon as it is released it will, of course, spring back to its original shape, whereupon the retainer 68 and bolt 66 may be readily applied. Preferably, a shake-proof lock washer 77 is inserted between cup 71 and the underside of the head of bolt 66.

Preferably, though not necessarily, the outer periphery of stabilizer 69 has a double chamfer, as illustrated at 78 to prevent this edge from digging into the diaphragm wall during periods of operation. It may be noted at this point that stabilizer 69 is adapted to flex and therefore approximately conform itself to the upper wall of the bladder in the event the bladder fluid accidentally leaks out and allows the pressure in the lower part of chamber C to drive the diaphragm to its upper limit. In such event, the interposition of the stabilizer between folds of the bladder and between the bladder and the lower end of plug 17 prevents chafing and undue wear on the bladder rubber.

I will first describe the action of the dampener when the liquid being handled is not of the thixotropic or crusting types spoken of in the introduction. The bladder is preferably precharged so it will be in position F, it having passed through position E in reaching this position F. In going from position D to position E there is a natural tendency for the diaphragm to fold, wrinkle and become locally off-center—obviously undesirable effects if not held to a minimum. In the illustrated device such effects are sufficiently minimized to insure fully efficient and long-life operation. Contributing to this end is the fact that the slant height X of the conical extent 46 of bladder base-portion 43 is made to be appreciably less than the radius Y of the bend-annulus 44 when the bladder is in equilibrium (position D). Also contributing is the pre-formation of the slant angle 60 of the conical extent so, when the diaphragm is in equilibrium, said angle is less than the angle 61 between plane A and a chord 62 drawn to that plane to the upper end of arcuate extent 42. In the illustrated case, angle 60 is about 30° as against the approximately 54° of angle 61.

Additionally contributing to the above end, is the stabilizer 69, for, as it progressively engages the extent 46, it has the effect of trusting that extent ahead of it through the median zone, more or less “ironing out” the wrinkles or folds as they start to form.

When in position E, the rubber of the diaphragm is unstretched, except slightly at bend 44. In going from position E to position F, the rubber making up wall 46 of the bladder is stretched, the upper part 42 of the bladder continuing to hug housing wall 41. On the other hand, due to the relative rigidity of bend 44, there will be a flattened or return-bend effect 44' which will tend to

stand the base portion 43, except for the stopper area, away from wall 15, thus developing a space 59. Subsequently, an upward surge of fluid through passage 33 overcomes the previously predominant pressure in the bladder and thus unseats valve stopper 49 to admit fluid to chamber C below the bladder. The lower part of the diaphragm then tends to “spring” back towards positions E and D. When the gas pressure again becomes predominant and re-seats the stopper, some fluid will be trapped in space 59 between return bend 44' and the seated stopper, and this trapped fluid will hold the affected part of the bladder from contacting the shell wall, thus preventing abrasive wear on the bladder. The rubber facing 52 is adapted to make a tight seal whereby the trapping of a relatively small amount of the fluid is assured.

When the liquid being handled is, for instance, thixotropic, or rapidly crust-forming, the tendency is that spoken of in the introduction. That is, if thixotropic, the suspension tends to gel in the more quiescent annular zones around the housing wall while the central “core” of the suspension body becomes very fluid due to the more pronounced movement of the central portion of the diaphragm and to the jetting effect as the material is discharged from the mud chamber. The jetting effect is increased by the venturi nature and streamlining of passage 33. These characteristics of passage 33 are helpful in that they so direct the incoming stream of liquid as to distribute sediment evenly over the shell walls, as explained in the aforementioned co-pending application, but the jetting effect during discharge has its disadvantages where the material is thixotropic, due to its production of a central column of low viscosity—for, if remedial provisions are not made, the stopper and lower end of the diaphragm then would tend to plunge downwardly through the low viscosity column, pulling the upper portion 41 of the bladder away from housing wall 14, rather than stretching diaphragm wall 46. The gel-like material would then build up progressively around the vertically elongated, unstretched bladder, and the volumetric capacity of the bladder would thus be progressively diminished until the pressure of the contained gas would so nearly approach the peak pressure of the pumped fluid that it would offer no effective dampening action.

However, stabilizer 69 prevents such disadvantageous diaphragm action, the stabilizer effect being illustrated in Figs. 4 and 5. In the first place, the stabilizer provides a radially extended, axially reinforced or stiffened central portion of the diaphragm which increases the cross-sectional area of the central core of the mud-laden material which is kept in a low-viscosity fluid condition by reason of agitation due to diaphragm reciprocation—thus correspondingly reducing the volume of the surrounding annulus of gel-like material.

In the second place, assume that the gel-like material has gathered beneath the diaphragm when the latter is in the equilibrium position D indicated by dotted lines in Fig. 4. The annulus of such material would appear, in cross section, as made up of the body of material M, shown in full lines, plus the then contiguous body M' indicated in dotted lines. Then, as the diaphragm descends towards E (Fig. 4) the stabilizer comes into engagement with diaphragm wall 46, backing it up and axially stiffening it so as to thrust the gel-like material ahead of it, the surplus being discharged through passage 33. By the time the diaphragm reaches position E, the gel-like material has the approximate cross-sectional shape indicated at M.

In going from position E to position F (Fig. 5) the stabilizer continues to axially back up and stiffen the diaphragm in a manner to sweep the gel-like material ahead of it, the diaphragm wall 46 being stretched in the process, rather than pulling diaphragm wall 42 away from shell wall 14—as would be the case if the stabilizer were not present. By the time stopper 49 is fully seated (Fig. 5)

there is left only the relatively small body M-2 of gel-like material between the diaphragm and the shell, this body being of insufficient volume to materially affect the volumetric capacity of the bladder and, in fact, having the beneficial effect previously spoken of in connection with trapped fluid in space 59.

Thus, at the end of the down stroke of the diaphragm, the bulk of the gel-like material will have been swept clear of the housing chamber so the volumetric capacity of the bladder will be nearly normal, and so diaphragm wall 46 will be in effective tension. Consequently, the entire device is in condition to continue to act effectively as a pulsation dampener in spite of the peculiar nature of the material being handled.

While I have shown and described a preferred embodiment of the invention, various changes in design, structure and arrangement may be made without departing from the spirit and scope of the appended claims.

I claim:

1. In a device of the character described, a body shell defining an interior chamber, a rubber diaphragm within the chamber and dividing the chamber into two pressure zones, there being a pair of fluid flow passages through the shell, and opening, one each, to said zones, one, at least, of the passages being coaxial with the diaphragm whereby the central part of the diaphragm moves axially towards and away from said one passage during diaphragm flexure in opposite directions, and a stabilizer mounted on said central portion at the side of the diaphragm remote from said one passage, said stabilizer having a radially outwardly extending portion overlying but unattached to the diaphragm in the region surrounding said central portion, said stabilizer comprising a member which is flexible and axially resilient.

2. A device as in claim 1, wherein said member is axially stiffer than is the diaphragm.

3. In a device of the character described, a body shell having upper and lower walls defining an interior chamber, a rubber diaphragm within the chamber, said diaphragm being pre-formed as a bladder which, when in equilibrium, has an upper portion substantially complementary to and engaging the upper shell wall, and a base portion movable axially of the chamber toward and away from the central portion of the lower shell wall, there being a pair of fluid flow passages opening through the shell, one to the interior of the bladder and the other to the chamber at a point below the bladder and in line with the axis thereof, and a stabilizer carried by the bladder and located centrally of the inner face of the base portion of the bladder, said stabilizer comprising a vertically flexible and resilient member having greater vertical stiffness than has the flexing wall of the bladder, said stabilizer being centrally fixed to said base portion of the bladder and having a radially outwardly extending portion overlying said base portion but unattached thereto.

4. A device as in claim 3, including reinforcement in the central zone of the base portion of the bladder, which central zone acts to close off said other passage when the bladder is fully inflated, said extension of the stabilizer extending radially outward beyond the reinforced zone.

5. A device as in claim 3, wherein the stabilizer, when in equilibrium, is disk-like in formation.

6. A device as in claim 3, wherein the stabilizer is made of rubber.

7. A device as in claim 3; wherein the stabilizer is made of rubber which is stiffer than is the rubber of the bladder, and, when in equilibrium, is disk-like in formation.

8. A device as in claim 3, wherein, when the upper

portion of the bladder complementarily engages the upper shell wall, the base portion of the bladder must be stretched by bladder inflation in order to reach the lower shell wall, and wherein the stabilizer allows such stretch without effective interference.

9. In a device of the character described, a body shell having upper and lower walls defining an interior chamber having the general shape-characteristics of an oblate spheroid arranged with its polar axis extending vertically, a rubber diaphragm within and coaxial with said chamber, said diaphragm being pre-formed as a bladder which, when in equilibrium, has an upper portion substantially complementary to and engaging the upper shell wall, and a base portion turned upwardly and inwardly to lie, in major extent at least, above the lower edge of said upper portion, there being a pair of fluid flow passages opening through the shell, one to the interior of the bladder and the other to the chamber at a point below the bladder, the axis of said other passage being coincident with the axis of the chamber, a centrally arranged stopper carried by said base portion and adapted to close said other passage when the diaphragm is fully distended by predominant fluid pressure existing within the bladder, and a stabilizer centrally attached to the inner face of the base portion of the bladder, the stabilizer and stopper being coaxial, said stabilizer having a vertically resilient, radially outwardly extending portion overlying, but unattached to the base portion of the bladder.

10. A device as in claim 9, wherein said stabilizer comprises a member of disk-like formation which is centrally attached to said stopper.

11. A device as in claim 9, wherein said stabilizer comprises a rubber member of disk-like formation, the rubber of the stabilizer being stiffer than the rubber of the bladder.

12. A device as in claim 9, wherein, when said diaphragm is in equilibrium, the base portion includes an upwardly pointing substantially conical extent and the radially outwardly extending portion of the stabilizer lies in a substantially horizontal plane and is thus angularly spaced from said conical extent.

13. An assembly for the purpose described, comprising a pre-formed flexible bladder having a central base portion adapted for flexible displacement along a central axis, a stabilizer mounted within the bladder, said stabilizer being connected to the base proximate said axis and having a portion extending radially outwardly relative to said axis in overlying but unattached relation to said base, said stabilizer portion being axially resilient and being adapted to flex when in contact with the inner surface of the base during said displacement.

14. An assembly for the purpose described, comprising a rubber diaphragm having a circular periphery, and a stabilizer comprising a member centrally attached to the center of the diaphragm and having a radially outwardly extending portion overlying but unattached to the diaphragm, said member being flexible and axially resilient and being of rubber which is stiffer than is the rubber of the diaphragm.
